UNITED STATES PATENT OFFICE.

DAVID L. GORDON, OF NEW YORK, N. Y.

LOCK-OPERATED CIRCUIT-CLOSER.

1,347,506.

Specification of Letters Patent. Patented July 27, 1920.

Application filed December 14, 1915, Serial No. 66,678. Renewed October 21, 1918. Serial No. 259,140.

To all whom it may concern:

Be it known that I, DAVID L. GORDON, a citizen of the United States, residing at New York, in the county of Bronx and State of New York, have invented certain new and useful Improvements in Lock-Operated Circuit-Closers, of which the following is a full, clear, and exact description, such as will enable others skilled in the art to which it applies to make and use the same.

This invention relates to alarm apparatus, and with respect to its more specific features, to burglar alarms.

One of the objects of the invention is the provision of a simple apparatus of the character referred to, wherein the alarm will be operated even upon a very slight disturbance of normal conditions.

Another object of the invention is to provide a practical apparatus of the character referred to wherewith once the alarm is sounded, it will continue to sound until purposely restored to its normal inoperative condition.

Still another object of the invention is the provision of an efficient device of the character referred to capable of being readily set to operate upon a minimum amount of unauthorized movement of the parts.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings forming part of this specification, and wherein similar reference characters refer to similar parts throughout the several views,—

Figure 1 is a face view of a portion of a door and jamb showing a lock associated therewith embodying one form of the invention;

Fig. 2 shows a vertical section through the keeper on the line A—A, looking toward the door, the circuit being shown in open condition;

Fig. 3 illustrates a horizontal section through the keeper on the line B—B, the circuit being shown in closed condition;

Fig. 4 is a perspective view of a circuit closer or terminal piece employed in the apparatus; and

Fig. 5 is a perspective view of a terminal piece which is to be attached to the inner side of the keeper.

Preliminary to a detail description of the embodiment of the invention illustrated, it is to be observed that a prime desideratum of alarms is that they shall operate, as far as practicable, upon the slightest tampering with the apparatus they are intended to guard, and that when set in operation they shall continue operating to give the alarm until rendered inoperative by some authorized means. The present invention fulfills these requirements and others in a simple and efficient manner.

The numeral 1 represents a portion of a door, or other closure, 2 indicating the jamb, 3 a locking bolt, 4 the casing of the lock, and 5 a manipulative knob or handle serving to throw the bolt 3 into or out of the keeper 6. These elements may be similar to those commonly employed to fasten doors. When the bolt 3 is in its keeper 6, attempts to force the door may be made; and such attempts will result in relative movement between the keeper and the bolt, the bolt, which is usually on the door, being moved toward the strike plate 7, of the keeper, upon pressure tending to force the door. In the present embodiment the bolt 3, when in locking position, is slightly spaced from the strike plate of the keeper, as indicated at 8, so that, upon attempting to force the door, the bolt 3 may move this slight distance before coming against the strike plate. Means are provided for forming a normally open electric circuit adapted to be closed by the movement of the bolt toward the strike plate, and in the present embodiment this normally open circuit includes a terminal interposed between the keeper and said bolt. This terminal consists of a flat metallic piece 9, fastened in stationary position inside the keeper by means of a pair of metallic securing bolts 10 and 11 passing through the piece 9, and the crown 12 of the keeper, these bolts being secured in position by metallic nuts 13 and 14 engaging threads on the bolts. On each bolt is also threaded a binding nut 15 which serves to secure thereto a conducting wire 16 in circuit with a source of electricity, as battery 17, and a signal, as an alarm or bell 18. The securing bolts and their nuts form, in fact, binding posts of the electric circuit, and one of them is in contact with the piece 9, as at 19, the other being insulated

100

105

110

from said piece, but in contact with the keeper, as at 20. The piece 9 is also insulated directly from the keeper by the interposition of insulating material 21.

- 5 The inner face of the stationary terminal piece 9 is adjacent the effective plane of the strike plate, but between said plane and the crown of the keeper, and immediately opposite this piece is a movable member, in the present embodiment a metallic conductor 22, the plane of the inner face of which is designed to intersect the space 8 between the bolt 3 and the strike plate 7. When the bolt 3 is in securing position, it lies against
- 10 or closely adjacent the inner face of the member 22, and a slight movement of this bolt toward the strike plate, as by an attempt to force the door, will move the member 22 a sufficient distance to close the circuit, in the present instance by moving the member 22 in contact with the stationary terminal 9.
- 15
- 20
- 25
- 30
- 35
- 40

To support the conductor 22 and guide it in its movement, it is provided with a metallic extension or stem 23, which bears in an elongated opening in the crown of the keeper and in contact with the keeper, passing through an opening in the piece 9, from which piece it is insulated, as shown at 24. The stem 23 projects outside the keeper for convenience of manual operation and preferably is threaded for the reception of a head or cap screw 25, which may be adjusted on the stem and secured thereto in relatively stationary position by a set screw 26. In order to vary the friction of the stem 23 in its bearing, a set screw 27 is threaded into the crown of the keeper and has its end directed against the stem 23. By turning screw 27 the resistance to movement of the stem, and consequently of the member 22, may be varied.

- 45 By the foregoing described construction it will be perceived that there is provided a construction capable of efficiently effecting the objects hereinbefore mentioned, as well as others. A very slight relative movement between the bolt 3 and its keeper, a movement so small that the door may not have
- 50 moved any substantial distance from the jamb, will cause the member 22 to make a sufficient movement to close the circuit and cause operation of the signal or alarm 18. In the present embodiment the member 22
- 55 is a conductor and also a movable terminal of the electric circuit, so that said relative movement causes the member 22 to effect closure of the circuit, thus operating as a circuit closer. The circuit having been
- 60 closed will remain closed, independently of further movement of the door, this result being accomplished, in the present embodiment, by the drag or friction of the stem 23 in the keeper, which serves to yieldingly hold the two terminals 9 and 22 in contact,
- 65

and will require some force to cause separation thereof. This force may be applied by manipulating the stem 23, as by pressing on the cap screw 25. It will be seen that once the bolt 3 has been moved sufficiently to effect contact between the terminals 9 and 22, the alarm will be operated and will continue to operate, even though the door be relieved of pressure and permitted to move in the opposite direction.

70 One of the important features of this invention is the extent of movement of the movable member 22. Whether it be a terminal of an electric circuit, a circuit closer adapted to bridge two terminals, or a member which, when moved, co-operates to effect movement of a third member to close a circuit, or otherwise, this member 22, for any installation, may be set to have a predetermined extent of movement, and by movement thereof to said extent the circuit will be closed. On account of the positive character of the parts and their position relative to each other, with no springs to move or to cause movement between the parts, an extent of movement of the movable member 22 may be accurately predetermined, and the circuit will be closed upon so much movement. This extent of movement may also be very slight without effecting the accuracy of operation. Should it be desired to alter or vary the extent of movement to accommodate some particular situation not adapted for the predetermined extent of movement for which the parts may have

90 been previously set, this may readily be accomplished by adjusting the cap screw 25 on the stem. It will be observed that the inner face of this screw lies opposite the crown of the keeper, and the keeper crown acts to limit the inward movement of the cap screw. When the cap screw is adjusted to a position permitting a certain amount of movement of the piece 22, the piece 22 may be pressed inwardly until the cap screw contacts with the crown of the keeper, thus setting the circuit in open condition with a gap of a predetermined amount between the movable member 22 and the stationary member 9, in the present instance the terminals. While the embodiment illustrated includes the adjustable cap 25, it is to be understood that, viewed in some aspects, the invention contemplates any device by means of which the distance of movement of the member 22 may be predetermined.

100 It will be observed that the movable member 22, viewed in some aspects, may be regarded as a portion of the keeper, for instance, as a movable strike plate, since, in the present embodiment, its movement in the direction of the opening of the door is limited by the stationary member 9 which lies in its path, and like the strike plate obstructs further opening movement of the door.

130

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

10 It is also to be understood that the language used in the following claims is intended to cover all of the generic and specific features of the invention herein described, and all statements of the scope of 15 the invention, which, as a matter of language, might be said to fall therebetween.

Having described my invention what I claim as new and desire to secure by Letters Patent is:

20 1. In an apparatus of the character described, in combination, a bolt, an electric circuit including a conductor movable to close the circuit by a door-opening movement of the bolt when the bolt is in locking 25 position, and means adapted to frictionally resist the circuit closing movement of said conductor, including hand operative means adapted to vary the frictional resistance.

2. In an apparatus of the character described, in combination, a bolt, an electric circuit including a conductor movable to close the circuit by a door opening movement of the bolt when the bolt is in locking position, and means adapted to adjust the 35 extent of the circuit closing movement of said conductor.

3. In an apparatus of the character described, in combination, a bolt, an electric circuit including a conductor movable to close the circuit by a door opening movement of the bolt when the bolt is in locking position, means adapted to frictionally resist movement of said conductor toward circuit closing position including hand operative means adapted to vary the frictional resistance, and means adapted to adjust the extent of the circuit closing movement of said conductor.

4. In an apparatus of the character described, in combination, a door, a bolt, a keeper, an electric circuit adapted to operate an alarm, a conductor movable to close said circuit by a door-opening movement of said bolt when in locking position, and hand-operated means adapted to set said conductor to move a predetermined distance to close said circuit.

5. In an apparatus of the character described, in combination, a door, a bolt, a keeper, an electric circuit adapted to operate an alarm, a conductor movable to close said circuit by a door-opening movement of said bolt when in locking position, and means adapted to vary the distance to be moved by said conductor to close said circuit.

6. In an apparatus of the character described, in combination, a door, a bolt, a keeper, an electric circuit adapted to operate an alarm, a conductor movable to close said circuit by a door-opening movement of said bolt when in locking position, hand-operated means adapted to set said conductor to move a predetermined distance to close said circuit, and means adapted to vary the distance to be moved by said conductor to close said circuit.

7. In an apparatus of the character described, in combination, a door, a bolt, a keeper, an electric circuit adapted to operate an alarm, a conductor movable to close said circuit by a door-opening movement of said bolt when in locking position, hand-operated means adapted to set said conductor to move a predetermined distance to close said circuit, and means adapted to keep said circuit closed after its initial closure independent of a door-closing movement of said bolt.

8. In an apparatus of the character described, in combination, a door, a bolt, a keeper, an electric circuit adapted to operate an alarm, a conductor movable to close said circuit by a door-opening movement of said bolt when in locking position, hand-operated means adapted to set said conductor to move a predetermined distance to close said circuit, means adapted to vary the distance to be moved by said conductor to close said circuit, and means adapted to keep said circuit closed after its initial closure independent of a door-closing movement of said bolt.

9. In an apparatus of the character described, in combination, a door, a bolt, a keeper, an electric circuit adapted to operate an alarm comprising two terminals, one of which is mounted on said keeper, one of said terminals movable toward the other under the influence of said bolt when the bolt is in locking position, and a push pin having a predetermined extent of movement adapted to set said movable terminal at a predetermined distance from the other terminal.

10. In an apparatus of the character described, in combination, a door, a bolt, a keeper, an electric circuit adapted to operate an alarm comprising two terminals, one of which is mounted on said keeper, one of said terminals movable toward the other under the influence of said bolt when the bolt is in locking position, a push pin mounted on said keeper adapted to move said movable terminal away from the other terminal, and means adjustable on said pin adapted to coöperate with said keeper adapted to permit the extent of said last-mentioned movement to be varied.

11. In an apparatus of the character described, in combination, a door, a bolt, a keeper, an electric circuit adapted to operate an alarm comprising two terminals, one of which is mounted on said keeper, one of said

terminals movable toward the other under the influence of said bolt when the bolt is in locking position, a push pin having a predetermined extent of movement adapted to set 5 said movable terminal at a predetermined distance from the other terminal, and a set screw adapted to vary the resistance to movement of said pin.

12. In an apparatus of the character described, in combination, a door, a bolt, a keeper, an electric circuit adapted to operate an alarm comprising a fixed terminal mounted on said keeper, a movable terminal having a stem supported on said keeper, adjustable means on said stem coöperating with said keeper to limit the movement of said stem in one direction, and a set screw adapted to press against said stem.

13. In an apparatus of the character described, in combination, a bolt and a keeper adapted to move toward and from each other, a fixed terminal piece supported by said keeper and interposed between said bolt and said keeper, a movable terminal piece 25 guided in a portion of said keeper and interposed between said bolt and said fixed terminal piece, hand operated means adapted to vary the resistance to movement of the movable terminal in its guide, an electric 30 circuit of which said terminal pieces are respective terminals, and a signal adapted to operate when said circuit is closed, movement of said bolt toward said keeper being adapted to effect contact between said terminals.

14. In an apparatus of the character described, in combination, a bolt and a keeper adapted to move toward and from each other, a fixed terminal piece supported by 40 said keeper and interposed between said bolt and said keeper, a movable terminal piece guided in a portion of said keeper and interposed between said bolt and said fixed terminal piece, means carried by said movable terminal adapted to predetermine the distance to which the movable terminal may be moved from said fixed terminal, an electric circuit of which said terminal pieces are respective terminals, and a signal adapted 45 to operate when said circuit is closed, move- 50

ment of said bolt toward said keeper being adapted to effect contact between said terminals.

15. In an apparatus of the character described, in combination, a bolt and a keeper adapted to move toward and from each other, a fixed terminal piece supported by 55 said keeper and interposed between said bolt and said keeper, a movable terminal piece guided in a portion of said keeper and interposed between said bolt and said fixed terminal piece, a head adjustably connected to said movable terminal and adapted to co-operate with said keeper portion to limit movement of said movable terminal away 60 from said fixed terminal, an electric circuit of which said terminal pieces are respective terminals, and a signal adapted to operate when said circuit is closed, movement of 65 said bolt toward said keeper being adapted 70 to effect contact between said terminals.

16. In an apparatus of the character described, in combination, a bolt and a keeper adapted to move toward and from each other, a terminal piece opposite the inner 75 face of the crown of said keeper and insulated from said crown, a pair of securing bolts passing through said keeper and said terminal piece, one of said securing bolts being in contact with said keeper and insulated from said terminal piece, and the other being insulated from said keeper and in contact with said terminal piece, a second terminal piece between said first-mentioned piece and said first mentioned bolt having 80 a stem guided in an elongated bearing in 85 said keeper, said stem having a threaded portion and a cap screw engaging said threaded portion, means adapted to hold said cap screw in stationary position on said stem, a source of electricity, an alarm, and a conductor electrically connecting said source and said alarm with said securing bolts.

In testimony whereof I affix my signature 95 in the presence of two witnesses.

DAVID L. GORDON.
